(57) **CLAIM**

The ornamental design for a curtain rod finial, as shown and described.

DESCRIPTION

FIG. 1 is a perspective view of a curtain rod finial design showing my new design.

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a top perspective view of the curtain rod finial, shown in an environment of use.

The broken lines shown in FIGS. 2-6 and 8 are for purposes of illustrating portions of the curtain rod finial that forms no part of the claimed design; the additional broken lines shown in FIG. 9 are for purposes of illustrating environmental subject matter only and forms no part thereof.
